UNITED STATES PATENT OFFICE.

JOSEPH ALFRED MILLS, OF EAST KIRKBY, ENGLAND.

CIRCULAR-KNITTING MACHINE.

Application filed September 12, 1924, Serial No. 737,323, and in Great Britain September 19, 1923.

This invention relates to improvements in circular knitting machines in which latch needles are employed, and its object is to produce on such machines, seamless garments or tubular fabrics which are fashioned by increasing or diminishing the number of needles which are in action from time to time, and thus actually increasing or diminishing the number of vertical wales at 10 different points in the length of the work, as is necessary in order to produce properly fashioned goods.

The invention may however in some cases be applied to circular web machines solely 15 for the purpose of providing in one and the same machine, facilities for producing tubular fabrics of varying dimensions.

Referring to the accompanying drawings, Fig. 1 is a sectional elevation, and

20 Fig. 2 a plan of a circular knitting machine to which my invention is applied.

Fig. 3 is an inverted plan of the cam ring for actuating the fashioning needles and the instruments cooperating with the same.

25 Fig. 4 is a plan, and

Fig. 5 an elevation showing the needle jack operating mechanism detached.

Fig. 6 is a view showing a complete set of 30 needle jacks disposed one behind the other.

Fig. 7 is a vertical section, and

Fig. 8 a plan of a segment of the machine.

Figs. 9 and 10 are corresponding views 35 to Figs. 7 and 8.

Figs. 7 to 10 are drawn to a larger scale than Figs. 1 to 6.

Like letters indicate like parts throughout the drawings.

In a circular knitting machine for producing plain fashioned tubular fabric construct-

40 ed according to my invention (see Figs. 1 and 2) part of the needles A are disposed in tricks in a vertical needle cylinder C, whilst the remainder B, hereinafter termed the fashioning needles, are disposed in the

45 upper face of an annular bed D which surrounds the needle cylinder C, which face is located a little higher than the upper end of the cylinder and in a plane at right angles to the axis of the cylinder.

50 The needles A in the cylinder C are disposed at regular intervals all round the latter, and are operated in the usual manner

by cams in a cam-ring E (see Fig. 1) engaging with butts A' at their lower ends.

The fashioning needles B which are disposed in radial tricks or recesses provided for them in the upper face of the annular bed D, are arranged with their hooked ends on the inner and their butted ends on the outer side of the said bed, and they are thus 55 disposed so as to draw their loops outwards, that is, in the same direction as the cylinder needles A, and as a result a plain fabric is 60 produced.

In the preferred arrangement, one fashioning needle B is employed to every three cylinder needles A, and they are arranged in the annular bed D at regular intervals, that is, three cylinder needles apart. The 65 arrangement of the needles B may however 70 be varied to suit different requirements.

The fashioning needles B are moved inwards by means of jacks G into the range of cams in a cam ring F, which latter is disposed above the bed D, and is connected to the cam ring E by a post E' (see Fig. 2). The needles B are then actuated by said 75 cams so as to knit the course, and are subsequently delivered clear of the cams again. If the needles B are to knit every course, 80 they must therefore be moved in every time by the jacks G. The cams in the ring F act on the butts B' at the outer ends of the needles, and the inner ends of the latter work through between two cylinder needles A, 85 passing from the outer to the inner side in order to clear their loops and take the thread from the feeder for the next course, and are entirely withdrawn from the cylinder needle when knocking over the loops and completing 90 a course.

The fashioning needles B thus each work between two cylinder needles A, but no extra space is left between the latter, and as the loops on the fashioning needles B are drawn 95 through in the same direction as those on the cylinder needles A, a plain effect is always produced by them as previously described, whilst the fabric is fashioned by putting more or less of the fashioning needles B into or out of action as the work proceeds.

When a fashioning needle B is for instance in action, it knits a vertical wale

which is disposed between the two wales produced by the two neighbouring cylinder needles A between which the fashioning needle B works, whilst on the other hand, when a fashioning needle B is put out of action, the wale produced by it is suppressed, and the two cylinder needles A on either side of it, knit vertical wales which are now the correct distance apart.

10 A seamless garment or fabric can thus be fashioned by starting for example to knit on all the cylinder needles A and all the fashioning needles B, and gradually reducing the number of the latter needles B in action, thereby narrowing the work at it proceeds.

In one arrangement for example, the fashioning needles B are subdivided into four groups, each of which is disposed in 20 a different segment of the machine, and one or more of the corresponding needle or needles in each group is or are put out of action simultaneously as hereinafter described, so that each narrowing will occur 25 at four or more points in the circumference of the work, and will be uniformly distributed round the tubular fabric, which may for example be a stocking leg.

When a fashioning needle B is put out 30 of action, it is necessary, in order to avoid a fault, for that needle to deliver its loop on to the cylinder needle A on the right or left of it, means are therefore necessary to effect this result, and such means will 35 be hereinafter referred to, after describing the arrangement for operating and controlling the fashioning needles B.

The jacks G in connection with the fashioning needles B are disposed in the same 40 tricks or recesses as their needles, and are adapted to engage with the outer end of the latter and move them inwards. The needles B are thus brought into action when the jacks push them inwards, and as previously 45 stated this action must take place every time they are required to knit. The inner end portions of the jacks G are arranged under the outer end portions of the fashioning needles B, and work horizontally and parallel to them.

These jacks G project on the exterior of the bed D in which they are located and their outer ends are stepped as shown in Fig. 6, so that the whole or any required number 55 of them can be acted upon by a cam plate H, by adjusting the height of the latter. As shown in Fig. 6 eight jacks are shown, and their outer ends are cut so that they go out of action one after the other as the cam H 60 is lowered step by step.

These jacks G may be distributed in any required order in the respective groups of needles B according to the order it is desired to put the said needles out of action.

65 Referring now to Fig. 3, which is an in-

verted plan of the cam ring F for actuating the fashioning needles B, a is the point where the needles B are pushed in by the jacks G and their butts are then delivered into the cam groove b, they clear their loops 70 and take the new thread at c, whilst d is the knitting cam which after knitting the course delivers the needles with their butts in line with the space e, that is, clear of the cam groove b.

The butts B' of those needles B which are not pushed in by their jacks G so as to enter the groove b, run into the outer space e and are moved in by the cam f far enough to cast off their loops, but not 75 so far enough to take the thread from the feeder, and they therefore automatically go out of action under these circumstances.

The blank space g in the cam ring is provided for removing damaged needles, 80 and may be filled-in by means of a readily removable part if desired.

The cam plate H which revolves with the cam ring E, acts on the outer ends of the jacks G and pushes them in in succession. 85 This plate H (see Figs. 1-4 and 5) is carried by a sleeve J' which slides vertically on a hollow vertical pillar J carried on the cam ring E, and it is lowered step by step, 90 by means of a stepped face cam K which is mounted on a vertical axle K' also carried on the cam ring E. The sleeve J' is provided with an arm J² which rests on the top of the cam K, and the latter is intermittently advanced by the following arrangement in order to raise and lower the cam plate H.

Attached to the underside of the face cam K, is a toothed wheel L which is geared to a pinion M on an axle M' (see Fig. 4) 105 carried by the cam ring E.

Mounted on the same axle M' as the pinion M, is a lever N provided with a pawl N' which engages with the teeth of the pinion M.

As the whole arrangement moves round with the cam ring E, a stud which is vertically adjustable is raised into the path of the free end of the lever N as required, and the latter is then actuated and advances the wheel L and cam K. The lever N is returned to its original position by means of a spring O, which is connected to an arm O' on the axle M' to which the lever N is also connected. N² is a pivoted spring-actuated check-pawl or check-lever provided with a projection which engages with the teeth of the wheel L, and which forms a resistance which prevents accidental and undesirable movements of the said wheel.

In order to bring all the jacks G into action simultaneously whenever it is required, a supplementary cam plate P which is pivoted on a part P' secured to the cam ring F, is moved into its operative posi-

tion by means of an incline Q' (see Fig. 5) on the upper end of a pin Q which works in the interior of the hollow pillar J , and this pin is provided with an arm Q^2 (see Fig. 1) and a downward extension Q^3 which bears on a cam K^2 in the interior of the stepped cam K .

The cam K it will be understood is providing for putting the fashioning needles B out of action in succession, whilst the cam K^2 is used to bring all the fashioning needles into action again simultaneously at the proper time, after putting the whole or a portion of them out of action in order to fashion the leg of a hose or other garment.

It will also be understood, that by controlling the rising movements of the stud which engages with the lever N by means of pattern chain mechanism for example, full automatic control is provided.

In order to insure that the fashioning needles B will under the peculiar circumstances under which they work, draw the same length of loop as the cylinder needles A , a result which is absolutely necessary in order to produce perfect work, a cam actuated instrument or jack R is provided in connection with each of said needles B , and these instruments are moved up and hold the work directly under each fashioning needle B as it is drawing its loop. The loops are therefore each drawn over an instrument, the position of each of which relatively to its needle during the knitting of a course, is controlled by cams, which latter can be adapted to actuate the instruments as is required to give perfect results.

These instruments R , shown more clearly in Figs. 7 to 10, are each disposed in a trick or recess provided for it at the side of its corresponding needle B , but in a sunk portion on the inner side of the needle bed F , and said jacks are formed with nebs R' which engage in and are actuated by a cam groove h (see Fig. 3) in the same cam ring F that carries the fashioning needle knitting cams. The inner ends of these jacks R are each provided with a part R^2 which is disposed parallel to the needle bed F , and is situated on the underside of its needle, and this part is formed with a forked or hollowed out extremity adapted to engage with and hold the work. The said parts R^2 are also each provided with a needle stop R^3 .

When a fashioning needle B is put out of action, its loop must for the reason previously mentioned be delivered on to the cylinder needle A on the right or left of it, and this is effected in the following manner. The fashioning needle B is held back owing to its butt being located in the cam space e (see Fig. 3) and at the same time its inner end is sprung sideways as shown in Fig. 10 in order to bring its loop directly over the cylinder needle A on its right, which latter

can then rise through the loop on the fashioning needle B . The latter is then subsequently moved in by the cam f previously referred to, so as to cast off or clear its loop and leave it solely on the cylinder needle A .

The ends of the fashioning needles B are moved sideways as to bring them in the correct relation relatively to the cylinder needles A in the act of transferring the loops as previously described, by means of pins S disposed in holes in the fashioning needle bed D . These pins S are provided with flats which are disposed close up to the sides of the needles B , and by moving these pins S angularly, the flats act on and spring the needles sideways as previously described. The stops R^3 on the jacks R are provided to limit the bending action of the needles B .

The pins S described are provided with arms S' on the underside of the bed D , and the arm or arms S' in connection with the needle or needles which are to transfer their loops, are as the bed moves round, engaged by the inner end of a slide T (see Figs. 9 and 10) which latter is moved in at the proper time to effect the required result.

The slide T described is moved in as required by means of a lever V (see Fig. 2) which is pivoted at V' to the fixed slide carrying bracket T' and is engaged by a vertical pin W^2 on a second lever W which is pivoted at W' to the cam plate H previously described, so that it descends with the latter.

When the cam plate H is moved down one step, the outer ends of the jacks G which are not in consequence moved inward by said plate, come in contact with the free end of the lever W , thereby actuating the latter and imparting the required inward movement to the slide T to effect the transfer of the loops on each of the fashioning needles in turn as they are put out of action.

The jacks G cannot be pushed in by the lever W owing to the butts B' on the corresponding needles B engaging at this time with and being held back by the rib j (see Fig. 3) between the cam groove b and outer space e in the cam ring F .

Widenings may be effected by reversing the operation described, that is, by gradually increasing the number of fashioning needles which are in action, but the formation of eyelet holes where the said needles come into action cannot be entirely avoided without transferring loops from the cylinder needles, and this presents considerable difficulties.

The defect referred to may however be minimized to a considerable extent by adopting the following course. When a fashioning needle is brought into action, its end is bent over by the means hereinbefore described, so that it first takes the thread a cylinder needle space to the right or left

of its normal position and subsequently returns to and continues to knit in its proper position.

In this case two small eyelet holes are formed instead of one large one.

In circular web machines for making seamless tubular fabrics, in which no fashioning or shaping is required, part of the invention described may be adopted for the purpose of providing in such machines facilities for making fabrics of varying widths.

For example a machine such as described may be provided with half as many fashioning needles as there are cylinder needles, and provision is made for bringing more or less of the former into action according to the dimensions of the tubular fabric required from time to time.

The invention is also applicable to circular rib machines as the use of the fashioning needles described is not affected by the presence of rib needles.

What I claim as my invention and desire to secure by Letters Patent is:—

1. In a circular knitting machine, the combination with a cylinder provided with cylinder needles, and a needle bed provided with fashioning needles which work cross-wise of the cylinder needles, and draw their loops in the same direction as the latter; of cam actuated instruments provided with end portions arranged under and substantially parallel to the fashioning needles, and which co-operate with the said needles and hold the work and permit each fashioning needle to draw its proper length of loop.

2. A combination of parts as set forth in claim 1, a single cam being provided to operate the said fashioning needles and also the said instruments, the latter being provided with projections which engage with the said cam.

3. A combination of parts as set forth in claim 1, the said instruments being provided with stops arranged to one side of the inner end portions of the fashioning needles and which operate to limit their movements when sprung laterally out of their normal positions.

4. In a circular knitting machine, the combination with a cylinder provided with cylinder needles, and a needle bed provided with fashioning needles which work cross-wise of the cylinder needles and draw their loops in the same direction as the latter; of cam actuated instruments provided with end portions arranged under and substantially parallel to the fashioning needles, and means for springing the inner end portions of the said fashioning needles laterally when they are put out of action, so as to transfer the loops from the fashioning needles to the cylinder needles.

5. A combination of parts as set forth in claim 4, the said fashioning needles being provided with controlling jacks, and the said means for springing the fashioning needles being actuated by the said controlling jacks.

6. A combination of parts as set forth in claim 4, the said fashioning needles being provided with controlling jacks, and the said means for springing the fashioning needles comprising oscillatory pins provided with surfaces for engaging with the fashioning needles, arms secured to the said pins, a slide carried by the said needle bed, and a pivoted lever operated by the said controlling jacks so as to press the said slide inwardly against the said arms and thereby move the said pins axially to spring the fashioning needles.

In witness whereof I have hereunto set my hand.

JOSEPH ALFRED MILLS.
